[57] CLAIM

The ornamental design for a soldering iron handle, substantially as shown and described.

DESCRIPTION

FIG. 1 is an isometric view of a soldering iron handle showing our new design;

FIG. 2 is a side elevational view thereof;

FIG. 3 is an end elevational view thereof showing the end which is not visible in FIG. 1;

FIG. 4 is an isometric view of a soldering iron handle showing a second embodiment of our new design;

FIG. 5 is a side elevational view of FIG. 4;

FIG. 6 is an end elevational view showing the end which is not visible in FIG. 4; and

FIG. 7 is an end elevational view of the end shown in FIG. 4.
